UNITED STATES PATENT OFFICE.

RUSSEL G. WOODWARD, OF WAUKEGAN, ILLINOIS, ASSIGNOR TO THE UNION SPECIAL SEWING MACHINE COMPANY, OF CHICAGO, ILLINOIS, A CORPORATION OF ILLINOIS.

SEWING-MACHINE PRESSER-FOOT.

SPECIFICATION forming part of Letters Patent No. 722,441, dated March 10, 1903.

Application filed September 1, 1899. Serial No. 729,193. (No model.)

To all whom it may concern:

Be it known that I, RUSSEL G. WOODWARD, a citizen of the United States, residing at Waukegan, in the county of Lake, State of Illinois, have invented certain new and useful Improvements in Sewing-Machines, of which the following is a description, reference being had to the accompanying drawings and to the letters and figures of reference marked thereon.

My invention relates to an improvement in presser-feet for sewing-machines, and has been designed especially for use on what is known as the "Union Special Yoke Ruffling Sewing Machine," upon which I made application for Letters Patent of the United States on the 20th day of July, 1898, Serial No. 686,444.

It is the object of the present invention to provide a presser-foot having a part which partakes not only of a tilting movement, but which when a seam is passing under it will rise bodily to allow it to pass under. This is especially useful in connection with a machine of the character described, where the presser-foot is made in two parts, one part bearing on that portion of the fabric to be ruffled, while the other bears on the thicknesses of goods not ruffled, for if the presser-foot has only a tilting motion on its pivot when a heavy seam or a high ridge of cloth is reached the foot will tilt when the projection strikes the toe of the foot, but will bind beneath the body of the part. So, also, if the foot has only a vertical bodily-sliding movement when the projection strikes the toe there will be a bind, which will last until such time as the ridge of the goods reaches the central point of the foot. By providing, however, an arrangement of feet in which the part bearing on the ridge both tilts and lifts bodily the foot will first tilt as the ridge or seam strikes and will then gradually rise bodily as the ridge or seam passes under it.

The invention therefore consists of a presser-foot having a part which both tilts and has a bodily-vertical movement.

It also consists of a presser-foot having a part which is pivoted to the main part, said part and its pivot being movable up and down.

Finally it consists in the matters hereinabove described, and referred to into the appended claim.

The invention is illustrated in the accompanying drawings, in which—

Figure 1 is a perspective view of a portion of a "Union Special Yoke Ruffling Machine," showing my invention applied thereto. Fig. 2 is a perspective view of the presser-foot. Fig. 3 is a vertical section of the presser-foot in a plane including the line 1 1 of Fig. 2. Fig. 4 is a cross-section on line 2 2, Fig. 3.

In the drawings, A represents the bed-plate, B the gooseneck, C the needle-lever, D the needle-bar, E the presser-bar, and F as a whole the mechanism supporting and actuating the ruffler-blade, all these parts being similar in construction and operation to corresponding parts shown and described in the application above referred to.

The presser-foot to which especially the present invention relates is shown with its shank 1 adapted to be clamped around the lower end of the presser-bar E. It is provided with the integral rigid part 2, adapted to bear on that portion of the fabric which is to be ruffled and united to the other portions of the fabric. The other portion 3 of the presser-foot has the upwardly-extending lugs 4, embracing the part 5, formed with the shank of the presser-foot and pivoted thereto by means of the pivot-pin 6. The pivoted portion 3 of the foot is provided with openings for the passage of the needles and bears on the portion of the fabric outside the line of ruffling and by reason of the fact that it is pivoted will tilt when an extra thickness of goods, such as a seam, passes under it. To permit of the part 3 also moving bodily as well as tilting for the purpose referred to in a former part of this specification, this part 5 where the pivot-pin 6 goes through it is vertically slotted, so that as the part 3 is pressed up by the action of the fabric beneath it the pivot-pin will slide in the slot 7. Normally the part 3 is kept pressed down to its work by means of the spring 8, secured to the shank of the foot by the screw 9, the free end of the spring resting upon the cross-bar 10, extending between the lugs 4.

Various minor modifications and changes in the construction of the presser-foot may be made without departing from the spirit of my invention.

5 Having thus described my invention, what I claim, and desire to secure by Letters Patent, is—

The herein-described presser-foot comprising the main or body portion adapted normally to bear on the fabric to be sewed, with a rigid projection arranged to one side of and above the main portion and having a transverse slot, a second portion having vertically-extending

walls embracing the rigid vertical part and provided with a pivot-pin passing through 15 said vertical embracing walls and loosely fitting the slot, with means for keeping said second portion normally depressed upon the fabric, substantially as described.

In testimony whereof I affix my signature 20 in presence of two witnesses.

RUSSEL G. WOODWARD.
